United States Patent Office

Des. 233,488
Patented Oct. 29, 1974

233,488

SOFT SURFACE FLOOR COVERING OR SIMILAR ARTICLE

Robert D. Mansolillo, Bloomfield, N.J., assignor to
Congoleum Industries, Inc., Kearny, N.J.

Filed Feb. 15, 1973, Ser. No. 332,778

Term of patent 14 years

Int. Cl. D6—04

U.S. Cl. D92—4 R

FIG. 2

Fig. 2

FIG. 1 is a top plan view of a soft surface floor covering or similar article showing my new design, a design unit being shown within the corner markings, the unit repeats in regular succession beyond the unit boundaries;

FIG. 2 is an enlarged view of a portion of FIG. 1.

The surface opposite to FIG. 1 is a conventional planar backing without ornamentation.

I claim:

The ornamental design for a soft surface floor covering or similar article, substantially as shown and described.
